US0D1002992S

(12) **United States Design Patent** (10) **Patent No.:** **US D1,002,992 S**
(45) **Date of Patent:** ** **Oct. 31, 2023**

(54) **THUMB SLEEVE**

(71) Applicants: **Victor Owens**, Benton, IL (US);
Victoria Womble Baker, Benton, IL (US)

(72) Inventors: **Victor Owens**, Benton, IL (US);
Victoria Womble Baker, Benton, IL (US)

(*) Notice: This patent is subject to a terminal disclaimer.

(**) Term: **15 Years**

(21) Appl. No.: **29/639,704**

(22) Filed: **Mar. 8, 2018**

(51) LOC (14) Cl. **02-06**

(52) U.S. Cl. USPC **D29/114**

(58) **Field of Classification Search**

USPC .. D2/617, 618, 619, 621, 622, 623; D29/113, D29/114, 116.2, 117.1, 117.2, 118, 120.1, 123 CPC A41D 19/00; A41D 19/01547, A41D 19/01558
